UNITED STATES PATENT OFFICE.

URI D. MANVILLE, OF NEW HAVEN, CONNECTICUT, ASSIGNOR TO THE ELM CITY COMPANY, OF SAME PLACE.

DESIGN FOR LABEL.

Specification forming part of Design No. **7,159**, dated February 10, 1874; application filed January 23, 1874.
[Term of Patent 14 years.]

To all whom it may concern:

Be it known that I, URI D. MANVILLE, of New Haven, in the county of New Haven and State of Connecticut, have invented a new Design for Label; and I do hereby declare the following, when taken in connection with the accompanying drawing and the letters of reference marked thereon, to be a full, clear, and exact description of the same, and which said drawing constitutes part of this specification, and represents a view of the label.

This invention relates to a design for form in which to set the letters or figures to indicate quantity, quality, or condition of the article to which it is applied, intended more especially for "tape trimming," "frilling," "puffing," and other manufactured trimmings; and the design consists in the outline or form of the label,

as shown in the accompanying drawing, and herein described.

From each side of a center swell, A, to the right and left, are flying ends B C.

The center is intended for trade or other mark, and the ends for descriptive matter, such as trade-name of the article to which the label is applied, date of patents, or other condition or quality of the article.

I claim as my invention—

The design for label, as shown and described, consisting of the center scroll A and flying ends B C.

URI D. MANVILLE.
